Technical drawing of a mechanical device, labeled Fig. 2, showing various numbered components. The drawing includes a main vertical assembly with a handle (4), a base (1), and a central column (10). A lever system on the left (12, 13, 14, 15, 16, 17, 18, 19) is connected to the main assembly. A complex linkage mechanism at the bottom (20, 21, 22, 23, 24, 25, 26, 27, 28, 29) is driven by a spring (23). Various parts are labeled with numbers 1 through 29.

UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

TRIPLE TANDEM-PRESSING-MACHINE MECHANISM.

Application filed August 9, 1924. Serial No. 731,039.

This invention relates to pressing machines, and has for its object a particularly simple and efficient operating mechanism, by which the machines are connected in series, whereby the operation of the operating member of each machine to apply pressure to the movable element or head of such machine releases the movable element or head of the next machine, so that, the next machine in the series opens, and the operation of the last machine in the series to close the head then opens the head of the first machine in the series.

The invention consists in the novel features and in the combinations and constructions hereinafter set forth and claimed.

In describing this invention reference is had to the accompanying drawings in which like characters designate corresponding parts in all the views.

Figure 1 is a plan view of a series of machines embodying my invention, the machine being shown diametrically.

Figure 2 is a side elevation of one of the pressing machines.

Figure 3 is a front elevation thereof, the movable head being broken away.

Figure 4 is a sectional view of the clutch mechanism of each machine.

Figures 5 and 6 are detailed views of portions of the connections by which the operating mechanisms of the machines are connected in series.

Figure 7 is a fragmentary sectional view of the operating means for each machine taken on the plane of line 7—7, Fig. 3.

1, 2 and 3 designate the machines, the operating members of which are connected in series, so that, when the power is being applied to the movable head of the first machine, the second machine opens, and when power is being applied to the second machine, the third machine opens, and when the third machine is operated to apply power thereto, the first machine opens.

The machines may be of any suitable form, size and construction, and in the illustrated embodiment of my invention it is shown as the type of machine including a stationary pressing element as a lower buck 4, a movable element or head 5, movable toward and from the buck 4, a power member 6, motion transmitting means between the power member and the head 5, and power

means for intermittently actuating the power member 6. The buck 4 is here shown as mounted upon a suitable frame A, and the head 5 is here shown as carried by a vertically movable lever or yoke 7, pivoted at 9 to the frame A or a standard 10 rising therefrom.

The power member is here shown as a vertically movable lever 6 pivoted at 11 between its ends to the frame near the bottom thereof. The motion transmitting means between the lever 6 and the head 5 in addition to the yoke 7, comprises toggle links 12 and 13 pivoted together at 14, the link 12 being pivoted at 15 to the rear arm of the yoke 7 and the link 13 being pivoted to the frame preferably on the same pivot 11 on which the power member 6 is mounted. In addition to these parts 12 and 13, the motion transmitting means comprises a link 16 pivoted at 17 to the rear arm of the power lever 6 and connected to the toggle by a lost motion connection, so that, it is normally ineffective to transmit motion to the toggle until the head 5 has been moved preliminarily by hand toward closed position. The link 16 preferably extends normally horizontally and is formed with a lengthwise slot 18 for receiving a pin 19 of an end 20 of the link 12. The yoke 7 is provided with a suitable handle 21. The operator in closing the machine takes hold of the handle 21 and pulls the head 5 downwardly toward the lower buck 4, and thus moves the links 12 and 13 toward a straightened position, carrying the link 16 into a nearly upright position. Preferably in order to bring these links 12, 13 and 16, into effective motion transmitting relation, the head 5 should be moved so close to the lower buck 4, or the work thereon, that there is not enough space left for the operator to have his hands or fingers between the pressing elements.

When the head has been preliminarily closed and power is applied to the lever 6, the link 16 will thrust upwardly as the pin 19 is in the lower end of the slot 18, and move the toggle links 12, 13 in nearly their dead center line. The head when operated is held closed by the power operated mechanism and opened by a counterweight 22 and a counterclockwise spring 23 upon release of said mechanism.

The power lever 6 is intermittently actu-

ated by an intermittently rotatable cam shaft 24 which makes a half revolution during each intermittent operation, this shaft 24 having a cam or eccentric 25 coaxing with a face 26 on the front end of the lever 6. The shaft 24 is journalled in a suitable clutch housing 27, supported by the frame A. 5

The source of power is preferably a constantly running electric motor 28, carried 10 by the frame, the armature shaft 29 of this motor having a worm 30 thereon, meshing with the worm wheel 31 mounted concentric with the shaft 24, and rotatable relatively thereto. This worm wheel 31 is connected 15 to and disconnected from the shaft 24 by a periodic or half revolution clutch. This clutch and also the worm wheel are located within the housing 27.

This periodic clutch includes a shiftable 20 clutch section 32 mounted on the shaft 24 to rotate therewith, and slidably axially thereof, and clutch pins 33 which are shiftable by the section 32 into and out of holes 34 in the web of the worm wheel 31. These 25 pins are guided in passages in a guide disk 35 mounted on the shaft 24, adjacent the wheel 31, and are pressed into their operated position by a pressure ring 36, acting against shoulders 37 on the pins, the motion being 30 transmitted to the pressure plate through springs 38, these springs yielding in the event the pins are not in alinement with the holes 34, and forcing the pins into the holes when the pins come into alinement with the 35 holes. A main spring 39 acts on the section 32 to shift said section to its out position. The section 32 is shifted manually by the operator either by a handle or by a pedal against the action of the spring 39 into its 40 "in" position, and is held in its "in" position during each half revolution by a suitable member as a cam ring 40 suitably fixed to the wall of the housing 27, this ring having diametrically opposite notches 41, 45 and the section 32 having followers 42 normally alined with the notches.

Shifting of the clutch section 32 to its "in" position against the action of the spring 39 carries the followers 42 out of the notches 41, and upon initial rotation of the clutch section the followers ride onto the high plane faces 43 of the ring 40 between the notches and hold the clutch section "in" until it has made a half revolution and the followers 42 again come into alinement with the notches 41.

The clutch section 32 of each machine is shifted to its "in" position by means of a rocking handle lever 44, Figs. 1, 3 and 7, 50 mounted on a rock shaft 45 suitably carried by a bracket 46 on the frame of the machine.

The shaft 45 or sleeve, is mounted upon a rock shaft 51 and connected thereto, to rock said shaft 51 when the lever 44 is operated 55 to effect operation of the shaft 51, and to

permit operation of the shaft 51 relatively to the sleeve. In other words, the shaft 45 is connected to the shaft 51 by a one way clutch constructed, so that, the shaft 45 may operate the shaft 51 but the shaft 51 can- 70 not transmit motion to the shaft 45.

As here shown each shaft 51 has a collar 52 thereon, having a single jaw or hook 53 extending under the handle lever 44. Thus actuation of the handle downwardly also 75 rocks the shaft 51, but rocking of the shaft downwardly does not rock the handle 44.

Each shaft 51 has an arm 47 thereon, co-acting with an arm 48 on the rock shaft 49 journalled in the clutch housing, the shaft 80 49 having a shifter arm 50 thrusting against one end of the hub of the clutch section 32. Movement of the handle 44 to cause the shafts 45, 51 and arm 47 to move in a clockwise direction, actuates the shaft 49 to shift 85 the clutch section 32 to its "in" position.

Each machine 1, 2 and 3 has a rock shaft 51, and handle 44, and the handle 44 of each machine operates to throw "in" the clutch of such machine to apply power to the press 90 head of that machine, and also operates to transmit the motion to the rock shaft 51 of the next machine in the series to throw "in" the clutch to actuate the cam shaft 24 of the next machine to permit the head of such 95 next machine to open, without interfering with the operation of the third machine in the series. The connection between the shaft or sleeve 45 of the first machine, and the shaft 51 of the second machine includes a link 54 100 pivoted to a rock arm 55 on the sleeve 45 of the first machine, and connected at 56 to one arm 60 of an angle lever pivoted at 61 to one side of the frame of the machine No. 2, the other arm 62 of the bell crank lever 60 105 being connected by a link 63 to a rock arm 64 fixed to the shaft 51 of machine No. 2. Thus upon the depression of the handle 44 of the machine No. 1, the clutch of machine No. 1 will be shifted "in" and power applied 110 to the head 2, and the motion thereof will be transmitted to the rock shaft 51 of machine No. 2, to throw "in" the clutch and permit the press head to open, without operating the handle 44 of machine No. 2.

The link 63 is shown as pivoted at 65 to a link 66 pivoted at 67 to one arm of the bell crank lever 62, and this arm is provided with a shoulder 68, thrusting against the link 66, so that, the motion of the handle 44 of the first machine will be transmitted through the link 54 and bell crank 60, to the links 66 and 63, but the movement of the shaft 51 of the machine No. 2, will not be transferred to the shaft 51 of the first machine owing to 120 the fact that the link 66, which is pivoted to the bell crank 60 at 67 will move away from the shoulder 68 as shown in Fig. 6, when the handle 44 of machine No. 2, is 125 operated.

The rock shaft or sleeve 45 of the handle 44 of machine No. 2, is connected to the shaft 51 of machine No. 3, by a link 69, bell crank lever 70, link 70^a, and rock arm 47 on the shaft 51 of machine No. 3. The arm 71 of the bell crank lever 70 and the link 70^a are of the same construction as the arm 62 of the bell crank lever 60 and link 63, as shown in Fig. 6, that is the arm 71 includes a link 71^a similar to the link 66 of the construction shown in Figure 6. Thus when the head of machine No. 2 is open, and the operator operates the handle 44 of machine No. 2, to throw "in" the clutch to apply power to the head of machine No. 2, the motion of the handle 44 is transferred to the clutch section of machine No. 3, to open machine No. 3, as machine No. 2, becomes fully closed, so that, now machines No. 1 and 2 are closed 20 and No. 3 is open.

The connections between the operating lever 44 of machine No. 3, and the rock shaft 51 of machine No. 1, whereby when machine No. 3, is fully closed the head of machine No. 25 1 opens, comprises a link 72 pivoted at one end to the arm 55 of the operating member or sleeve 45 of machine No. 3, and at its other end to one arm of the bell crank lever 73, pivoted at 74 to the frame of machine No. 2, 30 the other arm of this bell crank lever 73 being connected to one end of a link 75, the other end of which is pivoted at 76 to one arm of a bell crank lever 77, the other arm of which is connected by a link 78 to an arm 35 79 on the shaft 51 on the shaft of the frame No. 1.

The connection between the link 78, and the bell crank 77, is a pin and slot connection 40, and performs the same function as the shoulder 68 and link 66, Fig. 6, so that, during the operation of the lever 44 of machine No. 1, motion will be transmitted by this link 78 to the lever 77. Thus the handle 44 of each machine operates to effect the complete 45 closing of that machine and the opening of the next machine in the series. But operation of the handle 44 of any one machine does not effect the operation of any other machine preceding that machine in the series. For 50 example; the operating of the handle 44 of machine No. 1, causes machine No. 1 to close and machine No. 2 to open, but does not in any way affect machine No. 3, and the operation of the handle 44 of machine No. 2, effects 55 the complete closing of machine No. 2, and effects the opening of machine No. 3, but does not in any way affect machine No. 1, and the operation of the handle 44 of machine No. 3 effects complete closing of machine No. 3, and the opening of machine No. 1, but does not in any way affect machine No. 2. However, if the operator has closed 60 any one of the machines, say machine No. 2, and instead of proceeding to machine No. 3, 65 remains at work on machine No. 2, he can

operate machine No. 2 by depressing the handle 44, to open the machine No. 2. But the sequence of the operation of the machines of the series will be upset, as now machines Nos. 2 and 3 are both open at the same time. 70 The sequence can be readily restored by completely closing machine No. 2.

Although I have shown three machines connected in tandem, any number of machines may be so connected, but three machines are practically the limit that any one operator can take care of. 75

What I claim is:—

1. The combination of more than two pressing machines arranged in series, each machine comprising cooperating pressing elements, one of which is movable toward and from the other, a power member connected to the movable element for applying pressure thereto and means for effecting the application of power to the power member including a manually operable part, and connections between said parts of all the machines whereby the operation of said part of any one machine of the series operates 80 the corresponding part of the next machine in the series to open the same, and the operation of such part of the last machine of the series to close the last machine operates the part of the first machine of the series to 85 open it. 90

2. The combination of a plurality of pressing machines, each comprising cooperating pressing elements, one movable toward and from the other, a power member for applying pressure to the movable element, means for controlling the application of pressure to the movable element and the opening of the press including a manually operable part, the manually operable parts 100 of the machines being connected in series, whereby the operation of the manually operable part of any one machine to effect the closing of said machine actuates the part of the next machine to effect the opening 105 thereof, and connections between the manually operable parts of the machines, said connections including a one way motion transmitting device operable to transmit motion in one direction only, and to idle during 110 the transmitting of motion in the opposite direction whereby the operation of the operating part of any one machine is ineffective upon the operating part of any preceding machine in the series. 115

3. The combination of a series of more than two pressing machines, each machine comprising cooperating pressing elements, one of which is movable toward and from the other, a power member for applying 120 pressure to the movable element, and means for controlling the application of power to the power member and the opening of the press including a manually operable part 125 and motion transmitting elements operated 130

by said part and connections between the operating part of each machine and the motion transmitting element of the next machine in the series.

5. 4. The combination with a plurality of pressing machines, each comprising cooperating pressing elements, one movable toward and from the other, a power member for applying pressure to the movable element, 10 means for controlling the application of power to the power member, including two parts and a one way motion transmitting connection operable to transmit the motion of one part to the other in one direction only, 15 and permit relative movement of said parts in the opposite direction, one of said parts being a manually operable member and the other a motion transmitting member, and connections connecting the manually oper- 20 able part of each machine and the motion transmitting part of the next machine in the series.

5. The combination of a plurality of pressing machines, each comprising cooper- 25 ating pressing elements, one movable toward and from the other, a power member for applying pressure to the movable element, means for controlling the application of power to the power member comprising a 30 rock shaft, an operating member mounted on the shaft, a one way motion transmitting device between the operating member and

the shaft to transmit motion from the operating member to the shaft in one direction, the operating member of each machine being 35 connected to the rock shaft next in the series to operate said shaft, and the operating member of the last machine in the series being connected to the rock shaft of the first machine in the series. 40

6. The combination of a plurality of pressing machines, arranged in a series, each machine including cooperating pressing elements, one movable toward and from the other, power mechanism arranged to apply 45 pressure to the movable element, means for controlling the application of pressure by said mechanism to the movable element and to the releasing of said element from the power mechanism, including a manually operable member, connections between the manually operable member of each machine and the controlling means of the next machine, including a one way motion transmitting de- 50 vice for effecting the opening of the movable 55 element of the next machine in the series without effecting the operation of the preceding machine in the series.

In testimony whereof, I have hereunto signed my name, at Syracuse, in the county 60 of Onondaga, and the State of New York, this 28th day of July, 1924.

ALBERT B. CLISSON.
